(57) CLAIM

The ornamental design for a plastic grass deck tile, as shown and described.

DESCRIPTION

FIG. 1 is a top perspective view of a plastic grass deck tile, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of FIG. 1; and,

FIG. 9 is a partial enlarged view of FIG. 6.

The dashed broken lines in the figures are for the purposes of illustrating portions of the plastic grass deck tile, which form no part of the claimed design.

The dash-dot-dash broken lines are for notating enlarged views, and form no part of the claim design.

1 Claim, 7 Drawing Sheets
